UNITED STATES PATENT OFFICE.

DANIEL HOYT, OF EAST ORANGE, NEW JERSEY, ASSIGNOR TO THE NATIONAL LOCK WASHER COMPANY, A CORPORATION OF NEW JERSEY.

CURTAIN FIXTURE.

Application filed June 18, 1917. Serial No. 175,257.

To all whom it may concern:

Be it known that I, DANIEL HOYT, a citizen of the United States, residing in the city of East Orange, in the county of Essex and 5 State of New Jersey, have invented certain new and useful Improvements in Curtain Fixtures, of which the following is a full, clear, and exact description, such as will enable others skilled in the art to which it 10 pertains to make, construct, and use the same, reference being had to the accompanying drawings, and to characters of reference marked thereon, forming a part of this specification.

15 This invention relates to curtain fixtures wherein a spring roller is employed which constantly tends to wind the curtain up, and wherein the curtain fixture is located at the bottom of the curtain and operating in

20 grooves on the window frame, and which is designed to hold the curtain at any height of its travel. The fixture is specially adapted for use in curtains for car windows.

One of the objects of this invention is to 25 make a practically self-righting curtain fixture, which will hold strongly against upward movement and lightly against downward movement, containing but few component parts which can readily be assembled into a curtain by inexperienced workmen.

Another novel feature of my improved 30 curtain fixture is the holding means, comprising an independently-acting cam, which 35 will hold only when the fixture is in practically a horizontal position, and which will hold against downward movement, and which will also hold much more strongly 40 against upward movement, but which will yield to excess pressure to push the curtain up without releasing the cams.

I am well aware that curtain fixtures have heretofore been used wherein a cam has been employed as the holding member, as for instance, in my Patent No. 676,557, June 18th, 45 1901, in which device the cam will hold when the curtain fixture is in a tilted position, and will hold so strongly against upward pressure that the fixture has often

been injured or broken; then too, the construction is more or less complicated, causing it to be expensive to manufacture, and also requiring skilled workmen to assemble them properly. Other features have 55 also been found which have not been entirely satisfactory.

The tension placed on the spring roller by the workman hanging the curtain has very much to do with the operation of curtain fixtures, that is to say, too strong a tension 60 will cause most curtain fixtures to creep up from the bottom, and when but little or no tension is placed on the spring roller, some curtain fixtures which have no holding power against downward movement, will 65 creep down from the top of the window, due to their own weight and the jarring of the car.

Almost any of the curtain fixtures which are used on car windows today would be 70 satisfactory if the spring rollers were properly tensioned and if the fixtures were properly assembled and properly operated, but many workmen, through carelessness or ignorance, do not put the proper tension on 75 the roller, or they do not assemble the fixtures in the curtains and windows correctly, and again, many passengers do not operate them properly.

The primary object of this invention is to 80 simplify the structure of a cam curtain fixture, so as to render the same positive yet effective in operation, simple and inexpensive in construction, durable in use, one which is easily adjusted to car windows, 85 capable of holding in the lowering direction as well as holding against strong roller tension, and in which the holding power of the cams will yield to a strong force.

These objects I perform in the preferred 90 embodiment of my invention, which I have illustrated in the accompanying drawings, to which reference is had, and in which similar reference characters indicate corresponding parts in the several views.

95 While the preferred form of my invention is illustrated in the accompanying drawings, yet it is to be understood that minor changes

may be made without departing from the scope thereof.

In the accompanying drawings,

Figure 1 represents a front elevation of a 5 window, the casing being partly broken away, to illustrate the application and use of my improved curtain fixture.

Figure 2 represents an enlarged detail sectional view.

10 Figure 3 represents an enlarged fragmentary plan view; and

Figure 4 represents an edge view of one of the fixture heads.

In the drawings, 1 indicates a window 15 frame, 2 the groove formed therein, 3 an ordinary spring-tensioned curtain roller, suspended from the roller brackets 4 which are secured to the window frame 1, and 5 indicates the curtain which is attached to the 20 roller 3, which is constantly tending to wind the curtain up.

Located in the bottom of the curtain 5 is my improved cam curtain fixture 6, which is designed to hold the curtain at any height 25 of its travel in the window frame.

The fixture 6 comprises the ordinary tube 7, which extends the entire width of the curtain, at each end of which is located a fixture head 8, presently to be described. Each 30 head 8 is connected to the tube by a heavy metallic rod 9, one end of which is firmly secured to the head 8 and the other end extends into the tube 7 to near the center where it is connected to a finger-piece 10.

35 The finger-piece 10 is provided with a shank 11, arranged longitudinally in the tube 7, said shank 11 being of considerable length and provided with a screw-threaded aperture extending the length thereof. The inner end of the rod 9 is similarly threaded, and designed to have screw-threaded engagement with the shank 11 of the finger-piece

40 10. The distance which the rod 9 is screwed into the shank 11 determines the maximum 45 and minimum adjustment of the fixture head 8. The finger-piece proper is located outside of the tube 7 and guide-plate 13 and is connected with the shank 11 by a connecting member. The finger-pieces are designed to

50 be used in operating the curtain and fixture, the length of the slots 12 in the guide-plate determining the maximum movement of the head 8. Located on the inside of the tube 7 is a thrust member 15, formed by forcing 55 portions of the tube inward. On the rod 9 is placed a loose sleeve 14, the outer end of which bears directly against the head 8, said sleeve being adapted to move freely on the rod 9 and also freely within the tube

60 7. Against the inner end of the sleeve 14 and secured to the rod 9 is a washer 16, through which the rod 9 is freely slideable. Against the washer 16 and on the rod 9 is located a spring 17, and against the spring

65 17 is another washer 16, of such a diameter

that it cannot pass the thrust member 15 but through which the rod 9 can freely move. The washer 16 is forced along the rod 9 compressing the spring 17; thereafter the rod 9 is flattened or "winged" as shown at 18 to 70 hold the spring 17 partly compressed.

It will be readily understood that when the rod 9 is screwed into the shank 11 of the finger-piece 10 that the washer 16 will be bearing against the thrust member 15 thereby compressing the spring 17 which forces the loose sleeve 14 against the head 8 thereby pressing the head 8 outward from the tube 7. The length of the fixture may be adjusted by screwing up or unscrewing the 80 rod 9 into or out from the finger-piece shank 11.

The heads 8 are made of metal, shaped practically as shown, formed with two sides and a hollow chamber or channel between the 85 sides. Each head has an anti-friction roller 23 pivoted in each end. Midway between the anti-friction rollers 23 is located a cam member 24 pivoted below the center and designed to partially revolve on the pivot 25. 90 One portion of the cam 24 is designed to bear on the bottom of the groove 2 in the window frame. On the cam 24 and below the pivot 25 is formed a stop 26, designed to bear on the inner face of the head 8, which 95 limits the outward movement of the bearing face of the cam 24, and which bearing face should be slightly beyond the line of upper and lower anti-friction rollers 23. At the upper end of the cam 24 is formed an arm 27, 100 providing a bearing for the spring 28, preferably made from ordinary round spring wire and provided with one or more coils which engage with the stud 40 and which is located in the cam head 8 and constantly 105 tending to press the bearing face of the cam 24 outward.

When the curtain 5 is equipped with the spring roller 3 and the curtain fixture 6, the workmen should first wind the proper tension on the roller, place the same in the brackets 4, raise one end of the fixture, with the finger-pieces compressed, until it will enter the grooves. If the fixture is too long, screw up one turn on each head, or if too short, unscrew one turn on each head, repeating this operation until the proper length is secured, when the finger-pieces 10 will stand midway of the slots 12 in the guide-plate, and the cams 24 will be bearing 115 on the bottom of the grooves 2, as shown in Fig. 1.

When it is desired to raise or lower the curtain, the finger-pieces 10 should be grasped and compressed, thereby drawing 125 the heads 8 together, and freeing the cams 24 from the bottoms of the grooves 2 and the curtain will be free to be moved either up or down.

It will be understood that when the cur- 130

tain 5 is in the raised position, if there be little or no tension on the roller 3, the cam 24 bearing on the bottom of the groove 2 by the force of the spring 28 will not allow 5 the curtain fixture 6 to creep downward, but the fixture can readily be pulled down by grasping the bottom of the curtain, for the reason that the spring 28 is light, and will allow the cam to trail on a line with 10 the anti-friction rollers which will be rolling on the bottom of the grooves. It will also be understood that when the curtain is in the lowered position, if a strong tension is placed on the roller 3, the fixture 6 will not 15 creep up, as upward pull will cause the cams to open and hold the fixture against upward movement, but if extra force is applied to push the curtain up the springs 17 will yield and allow the fixture to be 20 pushed up before the fixture is broken or injured. The holding power of the cam in upward movement is only limited by the strength of the spring 17, which can be made as strong as desired. The holding 25 power of the bearing face of the cam, in the downward movement is entirely governed by the strength of the spring 28, which can be made as weak as desired. The strength of the spring 17 has no effect on 30 the cam in the downward movement. It will also be seen that if the fixture 6 is tilted out of the horizontal position, that one of the anti-friction rollers 23 will bear and roll on the bottom of the groove 2 and 35 lift the cam out of holding position.

In manufacturing these fixtures, the heads 8 are made complete and rigidly secured to the rod 9, then the loose sleeve 14, washer 16^a, spring 17 and the washer 16 are placed 40 on the rod 9, and with the spring 17 partly compressed, the rod 9 is winged, as shown at 18, these together forming one component part. The finger pieces 10 are placed in the slots 12 of the guide plate 13, 45 and the latter screwed to the tube 7, forming another component part.

In assembling the fixture 6, all that is necessary is to insert the first component part into the second component part and 50 screw the rod 9 into the shank 11 of the finger piece.

Experience has demonstrated that the organization above described is a highly efficient one, and while the device described 55 is the preferred embodiment of my present invention, I do not care to restrict myself to the exact details of construction, combination and arrangement herein set forth, it being obvious that minor variations thereof, 60 not involving the exercise of invention, may

be made by any skilled mechanic, and such departures from what is herein described and claimed I consider within the scope and terms of my claims.

Having thus described my invention, 65 what I desire to claim and secure by Letters Patent is:

1. A window frame having grooves, a curtain in the frame mounted on a spring roller constantly tending to wind the curtain up, a curtain fixture at the bottom of the curtain comprising a tube, elongated heads with shanks slidably mounted in each end of the tube, anti-friction rollers at the ends of the heads, springs in the tube 70 to force the heads outward and the anti-friction rollers in engagement with the grooves, a cam in each head, said cam being an arc of a wheel eccentrically pivoted in each head, the circular face of each cam 75 having a decreasing radius as it rolls downward and inward and an increasing radius as it rolls upward and outward, a spring in each head to force the circular face of the cam in strong traction contact with the 80 grooves and a stop on the cam below the circular face to limit the upward and outward movement of the cam, and finger-pieces to withdraw the heads and cams free from engagement with the bottom of the 85 grooves.

2. A curtain fixture head of the character described, a cam in the head comprising an arc of a wheel eccentrically pivoted in the head whereby it has a decreasing radius 90 when rolling downward and an increasing radius when rolling upward, a spring in the head forcing the cam in traction contact with the window frame, and means to limit the rolling movement of the cam. 95

3. A curtain fixture consisting of a tube, a spring pressed head located at each end of the tube, adapted to operate in grooves formed on a window frame, a cam pivoted in each head and having a circular face, a 100 spring within the head tending to force the cam in rolling contact with the bottom of the grooves, the cam being so pivoted in the head that the circular face has a decreasing radius on downward movement and 105 an increasing radius on upward movement, and means to withdraw the head and cam from said engagement.

This specification signed and witnessed this 28th day of May, 1917.
